UNITED STATES PATENT OFFICE.

JOSEPH FISCHER, OF BELLEVILLE, NEW JERSEY, ASSIGNOR TO MARCUS T. GOLD-SMITH, OF ESSEX COUNTY, NEW JERSEY.

DESIGN FOR A HANDBAG-FRAME.

56,915.

Specification for Design.

Patented Jan. 18, 1921.

Application filed March 5, 1920. Serial No. 363,565. Term of patent 3½ years.

To all whom it may concern:

Be it known that I, JOSEPH FISCHER, a citizen of the United States, residing in Belleville, in the county of Essex and State of New Jersey, have invented a new, original, and ornamental Design for a Handbag-Frame, of which the following is a specification, reference being had to the accompanying drawing, forming a part thereof.

The figure is a face view of a hand bag frame showing my new design.

I claim:

The ornamental design for a hand bag frame as shown.

JOSEPH FISCHER.
